UNITED STATES PATENT OFFICE

LOUIS L. RAYNOR, OF NEW ROCHELLE, NEW YORK, ASSIGNOR TO THE HYGIENOL CO. INC., OF NEW YORK, N. Y., A CORPORATION OF NEW YORK

POWDER PUFF AND METHOD OF MAKING SAME

Application filed May 14, 1929. Serial No. 363,029.

My invention relates to a new and improved powder puff and method of making the same.

One of the objects of my invention is to provide a powder puff having a loop which is securely connected thereto.

Another object of my invention is to provide a powder puff having a loop provided with an enlarged and stiffened head so that this head of the loop can be retained by the stitches which connect the two halves of the puffs to each other. It is to be understood that my invention is not to be restricted to the specific type of puff disclosed as it may also be applied to the flat type of puff which only has a single pile surface.

Another object of my invention is to provide a new and improved method of making the loops of powder puffs so that they can be securely connected to the puff.

Other objects of my invention will be set forth in the following description and drawings which illustrate a preferred embodiment thereof, it being understood that the above general statement of the objects of my invention is intended to generally explain the same and not to limit it in any manner.

Fig. 1 is an elevation showing how the improved loop is constructed.

Fig. 2 is an elevation of a single loop.

Fig. 3 is an elevation of a puff to which the improved loop is applied.

Fig. 4 is a side elevation of the puff shown in Fig. 3.

Powder puffs of the type illustrated are generally made by sewing two pieces or disks of pile material to each other, while the pile faces of said disks are adjacent each other. These disks are not completely sewed to each other so that they form a little bag or pocket which is turned inside out so that the pile surfaces of the disks are on the outside of the article. The article is then finished by hand. It has been customary to provide loops connected to powder puffs of the type illustrated herein, and to also provide loops for the flat pads which are well known to the trade. One of the disadvantages of these loops was that they easily pulled out of the puff and this has

been a source of considerable annoyance.

According to my invention, the loops L are formed from bendable cord material which is first sewed by means of stitches S into the shape shown in Fig. 1, so that each pair of loops L is separated by smaller base loops L'. A succession of loops L of any desired number can be readily formed, as shown in Fig. 1. The connected material shown in Fig. 1 is then cut to produce separate loop members L. Each of these loops L has a base portion which is stiffened by the stitches S and this base portion is wider than the narrow inner end of the loop. It is much more desirable to form the loop in this manner than to merely form a knot in the inner end of the loop because the stiffened and enlarged inner end of the loop enables it to be reliably held in position. When the two pieces of pile fabric are connected by stitches S' said stitches S' may either pass through the base portion of the loop or over the base portion of the loop at about the point indicated as S^a in Fig. 2.

The stitches S' are sufficiently close and tight to pass over and through the relatively narrow part S^a of the loop. The loop is therefore firmly held in position by means of the enlarged stiffened head thereof so that the loop can not be removed without rupturing the stitches S'. As shown in Fig. 3, the stiffened inner end of the loop L is between the central part of the puff and the retaining stitches S'. That is, the stiffened inner end of the loop is located inwardly with respect to the retaining stitches S'. It will be noted that the loop has a closed base which is enlarged and stiffened by means of the additional layers of material, said additional layers being in substantially the same plane as the loop.

I have shown a preferred embodiment of my invention, but it is clear that numerous changes and omissions could be made without departing from the spirit of my invention.

I claim:

1. A powder puff having a loop connected thereto by means of retaining stitches, said loop having an enlarged inner end comprising additional layers of the loop material which are connected to the body of the loop by stitches, said enlarged inner end be-

ing inwardly located with respect to the retaining stitches.

2. A powder puff having a loop connected thereto by means of stitches, the inner end of said loop being substantially closed, the material of said loop at said closed inner end having additional material connected thereto to form an enlarged inner end of said loop, said additional layers of material being integral with the loop and being in substantially the same plane as the material of said loop.

In testimony whereof I affix my signature.

LOUIS L. RAYNOR.
